STARTING AND OPERATING CIRCUIT FOR
ELECTRIC DISCHARGE DEVICESWilliam F. Hodge, Lyndhurst, Ohio, assignor to
General Electric Company, a corporation of
New York

Application December 7, 1945, Serial No. 633,382

5 Claims. (Cl. 315—96)

1

My invention relates to starting and operating arrangements for gaseous electric discharge devices.

An object of this invention is to provide a circuit arrangement whereby a pair of discharge devices may be started with but one starting device. Other objects and advantages of my invention will appear from the following description of species thereof.

The drawing is a diagrammatic representation of a circuit arrangement comprising my invention.

The circuit illustrated embodies two gaseous electric discharge devices 1 and 2 which may be positive column discharge lamp devices comprising elongated tubular envelopes or containers 3 and 4 having sealed into the ends thereof the thermionic electrodes 5, 6, 7 and 8 each herein illustrated as consisting of a coil (preferably a coiled-coil of wire such as tungsten coated with a material of high electron emissivity, such as an alkaline earth oxide like barium or strontium oxide or mixtures thereof). The envelopes 3 and 4 contain a gaseous atmosphere such as a rare gas like krypton, neon, argon, or mixtures thereof or a vaporizable metal such as mercury, preferably a mixture of a gas and vaporizable metal. The devices 1 and 2 may be low pressure positive column lamps of the fluorescent type with the envelopes coated internally with a suitable phosphor which under the influence of an electric discharge through, for example, a combination of a rare gas and the mercury vapor, produces fluorescence.

The devices 1 and 2 are respectively connected in series with suitable ballast impedances which may consist of resistances, for example in the form of incandescent tungsten filament lamps 9 and 10 or a single lamp containing two filaments which act as the ballasts 9 and 10, and inductance or choke coils 11 and 12. The ballasts 9 and 10 are connected on opposite sides of the lamps 1 and 2 from the choke coils 11 and 12. The devices 1 and 2 and their associated ballasts and choke coils are electrically connected in parallel with each other across a suitable source of current or power 19, 19', which for example may be a 118 volt, 60 cycle source, the choke coils being connected to opposite sides of the source 19, 19'.

The starting or heating circuit 13 embodies filamentary electrode 6 in series with a push button starting switch 14, a vibrator switch 15 with coil 16 and contacts 17, and filamentary electrode 7. A capacitance 18 of 0.01 microfarad rating is preferably connected directly across the

vibrator switch 15 and the starting push button switch 14.

In accordance with my invention one vibrator type starting device 15 and a push button switch 14 is used to start two discharge lamps. To start the lamp switch 28 is first closed, and then switch 14 is closed to complete a circuit from the power line 19 through the inductance 11, the lamp electrode 6 of discharge device 1, the push button switch 14, the normally closed contacts 17 and the coil 16 of the vibrator switch 15, the lamp electrode 7 of discharge device 2, the inductance 12, and the other power line 19'. In other words the cathodes 6, 7 and choke coils 11, 12 are all connected in series across the power source. The current flow in circuit 13 pre-heats filaments 6 and 7, and opens contacts 17 by means of the magnetic flux of coil 16 of the vibrator switch 15. When the circuit is thus interrupted, a very high voltage kick is obtained from the inductances 11 and 12 and applied across the lamp electrodes 5, 6 and 7, 8 of discharge devices 1 and 2 respectively. Inasmuch as the magnetic switch operates on each half cycle of current a series of voltage kicks will be applied to the lamp. Starting is substantially instantaneous for all practical purposes. If the lamp fails to light, a series of voltage kicks is obtained from the vibrator action of the magnetic switch 15 as it opens and closes. The high voltage impulses are repeated in very rapid succession so that the ionization produced in the lamp by the first voltage impulse is continued and is built up or reinforced by the second voltage impulse and also the third and so on until the lamp lights. After both lamps 1 and 2 have started, the push button switch is released to open circuit position.

The discharge devices may for example be 32 watt circular fluorescent tubes of 12 inch diameter containing a gaseous atmosphere of argon and mercury with a voltage drop of 85 volts at approximately .42 ampere. The ballast lamp and choke coil in series with it are rated at 33 volts .42 ampere and 35 millihenries respectively. Alternatively, one of the discharge devices may be 23 watt circular fluorescent tube of 8½ inch diameter containing a gaseous atmosphere of argon and vaporizable mercury with a voltage drop of 59 volts at approximately 0.42 ampere. The ballast lamp and choke coil in series therewith would be rated at 61 volts, 0.42 ampere and 35 millihenries, respectively. If desired, the ballast lamps 9 and 10 may be omitted and the inductive reactance of choke coils 11 and 12 increased to ballast the lamps.

If desired, pre-heating of the electrodes 6 and 7 may be dispensed with. In this case the starting circuit 13 is connected at one end between the lamp 1 and the inductance 11, and at the other end between lamp 2 and the inductance 12.

The vibrator switch 15 may be a normally closed but quick opening electromagnetic switch calibrated to open only on the A.C. voltage peak. As shown in Fig. 2 the switch is preferably of the vacuum type comprising a tubular envelope 20 with leads 21 and 22 sealed in one end of the envelope 20 and consisting of any suitable material for example a nickel lead 21 and a tungsten lead 22 with the former acting as the stationary component of the switch and the latter the spring component of the switch. A pair of soft iron discs 23 carrying tungsten contacts 24 mounted perpendicular to each other are fastened by suitable means to the ends of leads 21 and 22. Although the contacts 24 are normally closed they are shown in Fig. 2 in their open position for the sake of clearness. The coil 25 may for example be eight hundred turns of number 32 copper wire.

The push button starting switch may be replaced by a glow switch 14' indicated in Fig. 2. A species of this type of switch is disclosed in the United States Patent No. 2,329,134 issued September 7, 1943 to L. R. Peters. The glow switch 14' comprises a hermetically sealed glass envelope 26, a U-shaped electrode 27 comprising a thermally responsive bimetallic element welded to support 28, an electrode 29 comprising a metal rod such as nickel, and an ionizable gaseous atmosphere therein such as argon at a pressure of about 25 mm., helium at a pressure of about 100 mm., or a mixture of helium and 0.01 to 5 per cent argon at a pressure of about 100 mm.

The feature of employing a serially connected glow switch having normally open contacts and a magnetic vibrator having normally closed contacts for impressing a series of impulses of starting voltages across the electrodes of an electric discharge device for a predetermined period of time established by the closure of the glow switch contacts is disclosed and claimed in co-pending patent application Serial No. 616,904 of Royal F. Strickland filed September 17, 1945, and which is assigned to the assignee of this application.

With the arrangement shown in Fig. 2, when potential is applied to the circuit by closing the main line switch 28 (Fig. 1) the glow discharge starts in the glow switch, the gap between the switch electrodes is closed by the flexing of the bimetallic electrode to extinguish said glow discharge and to permit a heavier current to flow through the coils 25 of the vacuum vibrator switch. The extinguishing of the glow discharge permits the bimetallic electrode to cool and thus to flex back to its original spaced position with respect to the stationary electrode, thus breaking the series connection between the lamp electrodes after the filaments of the discharge devices have been heated to their operating temperature and the impressed transient voltage surge produced by the vacuum vibrator switch and the inductances have successfully started the discharge devices.

What I claim as new and desire to secure by Letters Patent of the United States is:

1. In combination, a pair of gaseous electric discharge devices each comprising a sealed envelope containing spaced electrodes, means connecting said discharge devices in parallel across

5 a source of power with an inductance in series with each discharge device, said inductances being connected to opposite sides of said source of power, and a starting circuit including switch means connecting said inductances in series 10 across said source of power for starting said devices.

2. In combination, a pair of gaseous electric discharge devices each having a thermionic cathode and a cooperating electrode, means to 15 connect said discharge devices in parallel across a source of power with an inductance in series with each device, and a heating circuit including starting switch means connecting a cathode of one device with the cathode of the other device 20 in series and in series with the said inductances across said source of power.

3. In combination, a pair of gaseous electric discharge devices each having a thermionic cathode and a cooperating electrode, means to 25 connect said discharge devices in parallel across a source of power with an inductance in series with each device, and a heating circuit including starting switch means connecting a cathode of one device with the cathode of the other device 30 in series and in series with the said inductances across said source of power, said starting switch means including a magnetic vibrator switch having normally closed contacts and a second switch in series therewith and capable of maintaining 35 the heating circuit closed until both lamps start.

4. In combination, a pair of gaseous electric discharge devices each having a thermionic cathode and a cooperating electrode, means to 40 connect said discharge devices in parallel across a source of power with an inductance in series with each device, and a heating circuit including starting switch means connecting a cathode of one device with the cathode of the other device 45 in series and in series with the said inductances across said source of power, said starting switch means including a magnetic vibrator switch having normally closed contacts and a manual switch in series therewith.

5. In combination, a pair of gaseous electric discharge devices each comprising a sealed envelope containing spaced electrodes, means connecting said discharge devices in parallel across a source of power with an inductance and a resistive ballast in series with each discharge device and on opposite sides of said device, said inductances being connected to opposite sides of said source of power, and a starting circuit including switch means connecting said inductances in series across said source of power for 55 starting said devices.
